UNITED STATES PATENT OFFICE.

DE FOREST B. CATLIN, OF MANKATO, MINNESOTA.

MASSAGE APPARATUS.

1,110,891.

Specification of Letters Patent. Patented Sept. 15, 1914.

Application filed December 31, 1913. Serial No. 809,786.

To all whom it may concern:

Be it known that I, DE FOREST B. CATLIN, a citizen of the United States, residing at Mankato, in the county of Blue Earth and State of Minnesota, have invented a new and useful Improvement in Massage Apparatus, of which the following is a specification.

The object of this invention is the production of a massage apparatus, which is simpler, more durable, more easily regulated by the user to vary the length of stroke of the reciprocable member and more effective and has greater range of regulation than in prior devices.

More particularly this invention is an improvement upon the apparatus disclosed in Patent Number 1,059,594, granted to me on April 22, 1913.

To this end my invention consists of the features of construction and combination of parts set forth in the following description and the novel features pointed out in the claims.

In the accompanying drawings forming part of this specification, Figure 1 is a side elevation of my invention; Fig. 2 is a plan; Fig. 3 is a plan of a detail, part of the structure being broken away and in section for the purpose of more clearly disclosing the structure; Fig. 4 is an elevation of a detail showing the parts which are illustrated in Fig. 3 partly broken away and in section; Fig. 5 is an end view of a detail partly broken away and in section; Figs. 6 and 7 are perspective views of details showing the opposite ends of the racks and the links by which the massage device is adapted to be secured to the apparatus for use; Fig. 8 is a perspective of a detail showing the construction by which the pitman is secured to the reciprocating element, and Fig. 9 is a side view of a detail showing the method of attaching the pitman to the crank disk.

In the patent above referred to, which was issued to me, the mode of varying the length of stroke of the reciprocable member for imparting a vibrating or rubbing movement to the massage device is by shifting the point of connection on a rocker element which is interposed between two pitmans. This is objectionable because it is too far from the person taking massage treatment to be regulated except by stopping the treatment. The construction is also objectionable because it has been frequently found to get out of working order. With the present in-

vention the mode of lengthening and shortening said stroke is by varying the distance between the holders of the massage device, thereby placing the means for changing the stroke within easier reach of the operator who is receiving massage treatment. The adjustment of the holders is also combined directly with the reciprocable member, thus rendering the apparatus free from troublesome repairs.

In the drawings, a suitable prime mover is employed and a base upon which all of the operating parts are adapted to be mounted.

A indicates one form of prime mover such as an electric motor, it being obvious that any other form of prime mover such as a gas or steam engine, water motor or mechanical drive mechanism may be employed effectively.

2 indicates a base and 3, a stand of suitable construction for supporting the reciprocable member, said stand being secured to said base such as by bolts 4. The motor shaft 5 has mounted thereon a crank disk 6 such as 6, which is connected to a reciprocable member B by a pitman 7, said pitman having a knuckle joint 8 selectively secured to the crank disk in one of the openings 9 by a pin 10. These openings are positioned at different distances radially from the center of said disk, so that the stroke of the pitman can be permanently changed when desired.

The reciprocable member B is in the form of an arm having substantially midway between its ends an enlarged portion forming a cup 11 which is closed on its front and rearward sides by plates 12 and 13 held by screws 14. This cup forms a pair of passages 15 and 16 (see Fig. 5) along the front and back edges of said arm, in which a pair of racks 17 and 18 are guided along and toward the middle portion of the arm. The ends of these racks have secured thereto a pair of guide loops 19 and 20, which are adapted to slide longitudinally upon the arm and form holders for links 21, there being one guide or holder on the outer end of each rack bar. These links are pivotally attached to the holders by pins 22. The teeth of the racks 17 and 18 face inwardly toward each other and mesh with the teeth of a pinion 23, said pinion being positioned in the cup 11 and carried by a shaft 24, which projects upwardly beyond the upper wall of the cup. The upwardly projecting

end of this shaft carries a handle 25 by which the shaft 24 can be turned to move the racks away from and toward each other. This movement is adapted to regulate the 5 distance between the link holders and thus adjust the length of the reciprocating stroke imparted by the racks to the massage device such as a belt of usual construction, the ends 26 of which are indicated in Fig. 2 attached 10 to the links 21 by short straps 27 and buckles 28. The upper and lower walls of the cup 11 are formed with a pair of gudgeons 29 which are journaled in supports 30 projecting forwardly from the upper portion of the 15 stand 3, the upper of said supports being in the form of a plate detachably mounted upon the stand by bolts 31. In this manner the reciprocable arm is pivoted between its ends to reciprocate in a horizontal plane and 20 the shaft 24 is journaled in the upper projecting gudgeons.

Reciprocating motion is imparted to the reciprocable member and the racks carried by said arm by the pitman 7 which is 25 coupled to the reciprocable member by the collar 33, and the knuckle joint 34. The knuckle joints 8 and 34 compensate for the swinging motion of the pitman in a vertical plane and the swinging motion of the reciprocating arm in a horizontal plane.

To hold the racks in longitudinally adjusted position a spring pressed lock pin 36 is slidably mounted in a socket 37 formed on the front cover plate 13, said pin having a 35 shoulder 38 by which the expansion coil spring 39 seated in said socket is adapted to force the pin toward the side of the rack bar 17. The side of the rack bar 17 adjacent the lock pin is formed with a longitudinal 40 series of indentures 40 which are in the form of shallow curved recesses in which the inner end of the lock pin 36 is adapted to engage. The lock pin has a rounded inner end which is adapted to be seated in one of 45 the indentures at a time thus holding the rack bar 17 normally from longitudinal movement. As the rack bar 17 is connected with the rack bar 18 by the intermediate pinion 23 both rack bars are adapted to be 50 held from movement by the lock pin. The engagement between the lock pin and the rack bar 17 can be overcome by turning the handle 25, the rack bars thereby being moved into adjusted position, whereupon the lock 55 pin 36 is adapted to again hold them normally from further movement along the arm. It will be noted that the handle 25 by which the position of the link holders is varied is conveniently accessible for any one 60 standing in front of the machine and receiving treatment by the massage device coupled to the links.

In operation the pitman moves in a vertical plane and assists in converting the rotary 65 motion of the crank disk into the reciprocating

ing motion of the member B. This reciprocating member B co-acting with the rack bars and the links, imparts reciprocating or vibrating movement to the massage belt or other device, the stroke of said belt being 70 regulated by the positioning of the holders 19 and 20 on the reciprocable member. This movement of the holders is according to their adjusted position from the axis on which the operating arm 10 reciprocates. 75 The rack bars have great range of adjustment, they being permitted to slide through passages in the holders to which they are not rigidly secured. In consequence the stroke of the massage belt may be regulated from a 80 small fractional part of an inch to a long stroke which is only limited by the size of the apparatus.

In accordance with the patent statutes, I have described the principles of operation of 85 my invention together with the apparatus which I now consider to represent the best embodiment thereof, but I desire to have it understood that the construction shown is only illustrative and that the invention can 90 be carried out by other means and applied to uses other than those above set forth within the scope of the following claims.

Having described my invention, what I claim as new and desire to protect by Letters Patent is:—

1. Massage apparatus, comprising, in combination, a reciprocable arm mounted between its ends to swing in substantially a horizontal plane, a pair of rack bars slidable 10 along the sides of said operating arm, a pinion having teeth meshing with the teeth of said rack bars, means for turning said pinion to slide said rack bars, a support in which said pinion and operating arm are journaled, 11 holders carried by the outer ends of said rack bars to which the ends of a massage device are adapted to be connected to receive reciprocating motion and means for reciprocating said operating arm, said rack bars co-operating with said operating arm and being adapted to vary the distance of said holders from the axis on which said operating arm is journaled to regulate the length of stroke imparted to said massage device.

2. Massage apparatus, comprising, in combination, a reciprocable arm, a pair of rack bars slidable along the sides of said operating arm, said operating arm having a recess between its ends, the sides of which form guides for said rack bars, a pinion having teeth meshing with the teeth of said rack bars and provided with means by which it can be turned to move said rack bars along the sides of said operating arm, a support in which said operating arm is journaled between its ends, holders to which the ends of a massage device are adapted to be connected secured to the outer ends of said rack bars and forming guides over said operating

- arm for the longitudinal movement of said rack bars, means for reciprocating said operating arm on its axis and means for holding the rack bars in longitudinally adjusted position on said operating arm, said rack bars being adapted by their longitudinal movement to vary the stroke imparted to said massage device by said reciprocable arm.
- 10 3. Massage apparatus, comprising, in combination, a reciprocable arm journaled between its ends to reciprocate on an axis, a pair of bars slideable along opposite sides of said operating arm, guides on said arm for said bars, holders to which the ends of a massage device are adapted to be connected

secured to the outer ends of said bars, means for sliding said bars on said arm to vary the distance between said holders, a support in which said operating arm is journaled, 20 means for reciprocating said arm and means for holding said bars in adjusted position on said arm, said bars being adapted by their adjustment to vary the length of stroke imparted by said arm to said massage device. 25

In testimony whereof, I have signed my name to this specification, in the presence of two subscribing witnesses.
